REFRIGERATING APPARATUS

Harry F. Smith, Dayton, Ohio, assignor to General Motors Corporation, Dayton, Ohio, a corporation of Delaware

Application March 29, 1935, Serial No. 13,713

9 Claims. (Cl. 62—108.5)

This invention relates to refrigerating apparatus and particularly to an apparatus of this character by which the freezing of water into ice blocks may be carried on automatically.

More specifically, it is an object of this invention to provide a mechanism which will automatically fill an ice mold with water, freeze the water into ice and remove the ice from the mold repeatedly and without the assistance or attendance of the user.

It is the general practice, particularly in refrigerators for household use to accomplish the freezing of ice by providing one or more ice trays or molds which may be filled with water by the user and placed in a compartment maintained at a temperature below the freezing point of water. When one or more blocks of ice is needed, the tray is removed from the freezing compartment and the necessary ice removed therefrom manually. The many inconveniences attendant upon this type of apparatus are well known and need not be enumerated here. According to the present invention, these difficulties are eliminated by the provision of an automatic ice block producing mechanism which freezes a quantity of water in a mold, removes the ice from the mold and automatically refills the mold for the next freezing of ice therein, the frozen ice blocks being delivered to a storage basket maintained at a temperature below freezing where the ice may be removed readily as needed.

Further objects and advantages of the present invention will be apparent from the following description, reference being had to the accompanying drawings wherein a preferred form of the present invention is clearly shown.

In the drawings:

Fig. 1 is a diagrammatic view of a refrigerating apparatus embodying the present invention;

Fig. 2 is a cross section on line 2—2 of Fig. 3 of the automatic ice producing mechanism illustrated in Fig. 1;

Fig. 3 is a cross section on line 3—3 of Fig. 2;

Fig. 4 is a fragmentary view corresponding to the upper portion of Fig. 2 showing the parts in another position;

Fig. 5 is a fragmentary view corresponding to the upper portion of Fig. 3 showing the parts in the position illustrated in Fig. 4;

Fig. 6 is a diagrammatic view disclosing the ice releasing mechanism of the present invention in neutral position and associated with the mold shown in dotted lines; and

Fig. 7 is a diagrammatic view similar to Fig. 6

disclosing the ice releasing mechanism in an operated position for releasing ice from the mold.

Referring now to Fig. 1, there is illustrated diagrammatically a refrigerating apparatus comprising a cabinet 10 having a food storage compartment 12. Within the cabinet 10 there is mounted a cooling unit 14 including an ice block producing mechanism later to be described.

Within the cooling unit 14, there is provided an evaporator forming part of an absorption refrigerating apparatus of well known construction. The absorption system also includes a generator-absorber 16 adapted to be heated at times by a burner 18 and to be cooled at other times by a cooling coil 20. A condenser 22 is provided intermediate the generator-absorber 16 and the cooling unit 14. The absorption system may be of any well known type provided with automatic control means 24 of any suitable type for controlling the burner 18 and the cooling coil 20 to intermittently apply heat to the generator-absorber during a generating period and cool the generator-absorber during the absorption period.

Referring now to Figs. 2 and 3, the combined cooling unit and ice block forming mechanism 14 comprises an outer metal casing 26 within which is mounted an evaporator. The evaporator illustrated comprises a tubular header 28 having a liquid refrigerant inlet and gaseous refrigerant outlet connection 30 which communicates with the condenser 22. Depending from the header 28 at the rear end thereof, is a tube 32 which extends to the bottom of the cooling unit. Near the bottom of the tube 32 a pair of conduits 34 and 36 communicate therewith and are bent into serpentine form to lie along the bottom and up the side portions of the walls of the cooling unit. The conduits 34 and 36 terminate inside the header 28 near the top thereof as shown at 38. A conduit 40 is provided inside the header 28 and extends downwardly to a point adjacent the bottom of the tube 32 for the purpose of emptying the liquid refrigerant in the evaporator when necessary for service operations. The tube 40 terminates in a normally closed, valved, connection 42 near the front of the cooling unit. The serpentine portions of the conduits 34 and 36 are imbedded in a quantity of "hold-over" material 44 which has the properties of high heat conductivity and high specific heat. The major portion of the header 28, however, is imbedded in a quantity of insulating material 46 having the property of low heat conductivity. A sheet metal inner liner 48 forms a storage compartment 50

30

50

55

which is maintained below the freezing point of water for the storage of ice blocks. If desired, a second compartment 52 may be provided for the freezing of ice blocks or desserts in the more conventional manner by the use of the tray 54.

Intermediate the compartment 50 and the header 28, there is provided a compartment 56 within which is located the ice freezing mechanism of the present invention. This comprises a pair of ice molds 58 extending longitudinally of the header 28 and secured thereto in intimate heat exchange contact therewith. Each of the molds 58 comprises a longitudinally extending vertical wall 60, a horizontal bottom wall 62 and a sloping side wall 64 together with suitable front and rear end walls 66 to form a water tight ice mold having an open top. Intermediate the end walls 66, there are provided dividing partitions 68 which have a portion thereof cut away to below the normal water level maintained in the ice mold so that the blocks of ice formed between the partitions 66 and 68 will be connected together by a small bridge of ice extending over the partitions 68.

In order to provide for repeated fillings of the ice molds automatically, there is mounted at one side of the cooling unit 14 and out of direct heat exchange relation thereto a water reservoir 10 within which water is maintained at a level to which it is desired to fill the ice molds. In the apparatus illustrated, the level of the water in the reservoir 10 is maintained by an inverted water bottle 72 providing a suitable barometric or other suitable water feed of well known construction. The reservoir 10 is in communication with the ice molds 58 through a conduit 74 which is unobstructed except when ice is formed at the end thereof adjacent the ice molds 58. The conduit 74 may, if desired or necessary, be insulated in the vicinity of the evaporator to prevent the cooling effect produced thereby from freezing water in this conduit.

In order to remove ice blocks formed in the molds 58 and to deposit them in the basket 76 provided at the storage chamber 50, an ejector mechanism is provided for each of the ice molds 58. This comprises a plurality of ejector members 78 pivoted at 80 to extensions 82 at both ends of the ice molds 58. The ejector 78 may be formed of sheet metal which is so bent as to extend over the end walls 66 and down into the ice molds 58 adjacent the end walls 66 and the central vertical wall 60. The ends of the ejectors 78 which extend into the ice molds 58 are provided with pads 84 formed integrally therewith and which normally lie snugly against the vertical wall 60. The front and rear ejectors 78 for each of the ice molds 58 are connected together by a strip member 86 having upturned portions 88 at both ends thereof.

The ejectors 78 are actuated by means of a bellows 90 which is rigidly mounted on an adjustable stirrup 92 within a tubular recess 94 formed in the header 28. The bellows 90 is filled with a suitable volatile liquid in order to make it responsive to changes in temperature of its environment. The movable end of the bellows 90 carries a plunger 96 which engages a lever 98 pivoted at 100 and having at its opposite end a portion 102 bearing against a bell crank lever 104 pivoted at 106. The bell crank 104 is connected to each of the forward ejector members 78 by means of a pair of links 108.

In operation, the cooling unit 14 is intermittently cooled and heated by the absorption re-

frigerating system having its evaporator incorporated therein. During the cooling or absorbing portion of the cycle, the refrigerant vaporizing in the conduits 34, 36 and in the header 28 withdraws heat from the metallic casing 26 and from the chambers 50, 52, and 56, thus maintaining the food compartment 12 and the ice storage and dessert freezing compartments at the proper temperatures. Heat is also withdrawn from the ice molds 58 by the refrigerant vaporizing within the header 28. Assuming the water bottle 72 to be filled, the molds 58 will likewise be filled with water to the level maintained in the reservoir 10. During the normal continuation of the cooling cycle, the water in the molds 58 is frozen into ice blocks. As soon as the heating or generating portion of the cycle commences, heat is applied to the cooling unit, due to the warm liquid refrigerant entering the same from the condenser 22. The hold-over material 44 tends to prevent any substantial increase in temperature in the compartments 12, 50 and 52. The insulating material 46, however, permits a sharp rise in the temperature of the header 28, ice molds 58, and the associated mechanism. The volatile liquid in the bellows 90, therefore, expands and tends to push the lever 98 to the left in Fig. 3. As long as the ice blocks are bonded to the ice molds 58, substantially no movement of the plunger 96 is possible. However, when sufficient heat has been conducted to the molds 58 to free the ice blocks from the molds, the pressure exerted by the bellows 90 quickly moves the lever 98 to the left, causing the bell crank 104 to rotate in a clockwise direction lifting ejector members 78 to the position illustrated in Fig. 4. In moving to this position, the pads 84 carried with them the ice blocks 110 which then drop by gravity into the basket 76 for storage. It will be noted that ice formed in each mold 58 is in the shape of a long block which is nearly severed at each place where a partition 68 was positioned. The small bridge of ice connecting the several portions of the long block is strong enough to permit removal of the long block from the mold as one piece but may be easily broken manually whenever a small piece of ice is required from the basket 76. Upon removal of the ice blocks 110, the molds 58 will automatically be filled from the reservoir 10 up to the level maintained in that reservoir. As soon as the heating or generating cycle is terminated and the cooling or absorbing cycle is again started, the temperature of the bellows 90 rapidly drops, permitting the ejectors to return to the position illustrated in Fig. 2. At this time, the water in the ice molds 58 is still unfrozen so that the ejectors may move readily through the water to their positions at the bottom corners of the molds 58. Preferably, the size of the water bottle 72 is so proportioned with respect to the size of the basket 76 that a single filling of the bottle will produce enough ice to fill the basket 76. Thus, it is possible for the user to fill the bottle 72 and without further attention be assured of the manufacture of sufficient ice blocks to fill the basket 76. Likewise, as soon as the basket 76 is thus filled, the production of ice blocks is automatically terminated, inasmuch as the supply of water to fill the molds 58 is thereby exhausted.

Thus, the present invention provides for the automatic manufacture of a plurality of ice blocks by repeatedly freezing water in a set of molds without attention from the user other than that necessary to provide a supply of water to be frozen. It will be understood, of course, that 75

other well known means may be provided for maintaining a constant level of water supply, for example, the reservoir 70 may be connected to a suitable source of water under pressure, for example, the city water mains and may be provided with suitable level controlling means such as a float valve or overflow device for insuring the constant maintenance of a proper water level in the reservoir 70. It will be noted, however, that provision of an unlimited water supply for the reservoir 70 makes it necessary to remove ice blocks from the basket whenever the same becomes filled in order to avoid interference with the normal operation of the ejecting mechanism.

While the invention has been illustrated in connection with an intermittent absorption type of refrigerating apparatus, it will be understood that its advantages are not limited to the incorporation thereof with any particular type of refrigerating apparatus and that other refrigerating systems may be used with the invention so long as provision is made for interrupting the cooling cycle and for the application of heat to the ice molds either from the refrigerating system itself, from an external source or from the heat applied to the cooling unit by the circulating medium within the compartment 12. Likewise, while the invention has been illustrated and described in connection with its use for freezing water into ice, it will be understood that it may be used for other congealing operations and that wherever the terms water and ice are used in the specification and in the appended claims, it will be understood that the terms are to be construed broadly to include other comparable materials in which a change of state from the liquid to the solid may be induced by the withdrawal of heat therefrom.

While the form of embodiment of the present invention as herein disclosed constitutes a preferred form, it is to be understood that other forms might be adopted, all coming within the scope of the claims which follow.

What is claimed is as follows:

1. Refrigerating apparatus comprising in combination a stationarily mounted cooling unit, means for alternately cooling and heating said unit, an ice mold in thermal contact with said cooling unit, and means movable relative to said cooling unit automatically in response to the application of heat to said unit for ejecting ice from said mold.

2. Refrigerating apparatus comprising in combination a stationarily mounted cooling unit, means for alternately cooling and heating said unit, an ice mold in thermal contact with said cooling unit, means for storing ice in said cooling unit, and means movable relative to said cooling unit automatically in response to the application of heat to said unit for ejecting ice from said mold into said last named means.

3. Refrigerating apparatus comprising in combination an ice mold, a water supply means for substantially filling said mold with water, means for cooling said mold, means for removing ice frozen in said mold, means for storing ice removed from said mold, the water in said water supply means being so proportioned to the pro-

duction of ice that when a quantity of ice sufficient to fill said storing means has been produced the water in said supply means will be exhausted.

4. Refrigerating apparatus comprising in combination a stationarily mounted cooling unit, means for intermittently cooling said unit, an ice mold in thermal contact with said cooling unit, and means movable relative to said cooling unit automatically between cooling periods thereof for ejecting ice from said mold.

5. Refrigerating apparatus comprising in combination a cooling unit, an ice mold, means for filling said mold with water to be frozen, and means movable relative to both said cooling unit and said mold for removing ice from said mold, said last named means being actuated automatically in response to the application of heat to said cooling unit.

6. Refrigerating apparatus comprising in combination an ice mold, stationary means for cooling said mold, means for removing ice frozen in said mold, and means operated in response to a rise in temperature of said cooling means for moving said last named means relative to said stationary cooling means and said mold.

7. Refrigerating apparatus comprising in combination an ice mold, stationary means for intermittently cooling said mold, a member other than said mold for engaging the block of ice formed in said mold, and means responsive to a temperature rise at said cooling means for causing sufficient relative movement between said stationary cooling means and said member to remove the ice block from the mold.

8. Refrigerating apparatus comprising in combination, a cooling element, means for circulating a cooling medium to and from said element to cause same to produce a refrigerating effect, an ice mold carried by said cooling element in intimate heat exchange relation therewith, ice ejecting means normally positioned in said mold and movable relative thereto and to said cooling element for removing ice from the mold, means for actuating said ice ejecting means, said last named means including a thermostat responsive to a change in temperature of the refrigerating effect produced by said cooling element.

9. Refrigerating apparatus comprising in combination, a cooling member, means for circulating a cooling medium to and from said cooling member to cause same to produce a refrigerating effect, an ice mold member in intimate heat exchange relation with said cooling member, said members being rigidly secured together to prevent movement thereof relative to one another, ice releasing means associated with said mold member, said ice releasing means including an ice ejecting portion normally disposed in the mold member and an actuating portion extending outwardly of said mold member, means for moving said outwardly extending portion of said ice releasing means to cause movement of said ice ejecting portion thereof relative to said mold member, and said last named means being operable automatically in response to conditions of said refrigerating apparatus for liberating ice from said mold member.

HARRY F. SMITH.
